DIAPHRAGMS FOR FLUID-FILLED PAD BOXES

John William Pratt, Leicester, England, assignor to United Shoe Machinery Corporation, Flemington, N. J., a corporation of New Jersey

Application November 10, 1954, Serial No. 468,115

Claims priority, application Great Britain
November 14, 1953

2 Claims. (Cl. 12—38)

This invention relates to improvements in shoe bottom pressing apparatus and particularly to diaphragms for fluid-filled pad boxes.

The illustrated apparatus is especially suitable for attaching soles or half soles to the bottoms of shoes by means of a suitable adhesive. In this work, especially in repair work, it is usual to employ presses of the type disclosed in United States Letters Patent No. 1,901,546, granted March 14, 1933, in the name of George H. Barge, and No. 2,657,406, granted November 3, 1953, in the name of Frank C. Choice, in which a cemented sole or half sole is pressed against a previously cemented shoe bottom by means of a pad box comprising a hollow metal receptacle having clamped about its rim a flexible diaphragm, the pad box being adapted to contain fluid, preferably, water, which permits the diaphragm to conform to the shape of the shoe bottom and offers resistance so that the necessary pressure may be exerted upon the shoe to effect the necessary pressure may be exerted upon the shoe to effect attachment of the sole to the shoe. Means is usually provided for heating the water to accelerate the drying of the cement.

Diaphragms made of canvas-reinforced rubber for use with this type of shoe bottom pressing apparatus are well known and have produced good results when operating on men's shoes having reasonably flat bottoms. When, however, shoes to which high heels are afterward to be attached are being operated upon, rubber blocks suitably shaped to fill in the gap between the shank portion of the shoe bottom and the relatively flat diaphragm are sometimes provided. These, however, tend to prevent the conduction of heat from the pad to the shank portion of the shoe bottom, thus preventing acceleration of the drying of the cement in that portion. There is also a tendency for the canvas reinforcement to fracture at points where the diaphragm is repeatedly flexed, for example along the inside edge of the clamping member which holds the diaphragm to the receptacle.

Diaphragms unreinforced with canvas have been used to apply suitable pressure to the arched shank portion. These, however, while being sufficiently flexible to apply pressure to the shank portion, usually distend undesirably around the sole edge and require the use of a mask plate to prevent upward distortion of the marginal portion of the sole around the forepart of the shoe. Moreover, unreinforced diaphragms also extend upwardly around the inner edge of the aforesaid clamping member and thus have a tendency to crack in this locality. Furthermore, when high-heeled shoes are being half-soled, the necessary placing of the forepart portion of the shoe bottom on the pad in such a position that the heel of the shoe projects downwardly in front of the pad box allows the unreinforced diaphragm frequently to balloon at the forward edge of the box. This has a tendency to push off the heel of the shoe.

2

One of the various objects of the invention is to provide a more durable shoe bottom engaging diaphragm for pad boxes which shall be sufficiently flexible to operate efficiently in the arched shank portion of a shoe bottom and yet will not balloon or distend undesirably in the manner above described.

With this object in view, the illustrated apparatus is provided with a shoe bottom engaging diaphragm of rubber in which, over the greater portion of its area, 10 is molded two layers of nylon mesh for the purpose of reinforcement and of reduction of stretchability and wherein the nylon reinforcement is omitted from the region of the diaphragm which normally engages the shank portion of the shoe.

15 With such an arrangement the portion of the diaphragm having no reinforcement will be more flexible and extensible than the remainder of the diaphragm and will swell up against the arched portion of the shoe bottom when pressure is applied so that pressure will be efficiently applied to that portion while the remainder of the diaphragm will be sufficiently reinforced to prevent undesirable ballooning without the use of a mask plate, and the conduction of heat to the shoe will be unimpaired.

20 The above and other features of the invention will be better understood from the following detailed description when read in connection with the accompanying drawings and will be pointed out in the appended claims:

In the drawings—

30 Fig. 1 is a view in perspective of the shoe-engaging portion of a pad box;

Fig. 2 is a fragmentary enlarged section through the portion of the diaphragm where the unreinforced portion is located;

35 Fig. 3 is a fragmentary longitudinal section of the diaphragm shown as conformed to the shank portion of a shoe pressed thereon;

Fig. 4 is a fragmentary plan view of the diaphragm; and

40 Fig. 5 is a fragmentary view showing that the margins of the openings in the nylon are pined, the showing of the mesh of the nylon being here omitted for the sake of clarity.

The illustrated apparatus is a shoe bottom pressing pad which is similar to that disclosed in the Choice patent referred to above. As in that patent, the present pad box comprises a hollow metallic receptacle 10 open at its top and front and having a diaphragm 12 which extends across the top and down the front portion and which is attached thereto by a clamping member 14 bolted to a flange of the receptacle. The pad is adapted to contain liquid, preferably water. The diaphragm 12 is made from a nylon reinforced rubber sheet, the nylon reinforcement consisting of one or more, preferably two, sheets of nylon mesh fabric 16, 17 embedded therein. Each sheet of nylon mesh, however, does not extend all over the diaphragm but has an opening 18 therein, as indicated by the dotted line in Fig. 1. The opening in one of the sheets of nylon 16 is preferably some 4½ inches wide at its rear end and some 3 inches wide at its forward end, the length of the opening from front to rear being some 6 inches. The size of the opening in the second sheet 17 of nylon mesh differs from that of the first sheet by approximately half an inch in length and in width so that the diaphragm is generally reinforced by two sheets of nylon mesh molded therein but has a portion 20 where there is no reinforcement and which consists solely of rubber which is preferably thickened in the portion 20, that is, in the region of the opening 18 in the nylon, the rubber becoming gradually thinner in the region under the margin of the opening, the purpose being to in-

crease the strength of the diaphragm in the unreinforced portion.

Preferably also, as indicated in Fig. 5, the margins of the openings in the nylon sheets 16, 17 are pinked, the notches of the pinking extending about an inch from the edge of the opening 18, and the points of the pinking in the two sheets being preferably in staggered relation to each other, the purpose of the pinking being to increase the bond between the nylon sheets at the margin of the opening 18 with the rubber in which they are embedded.

The openings in the nylon register with each other so that around the edge of this unreinforced portion there is a margin 22 of approximately one-quarter inch in width which has only one thickness of reinforcing material. This is to minimize any tendency for the unreinforced portion of the diaphragm to flex sharply at its junction with the reinforced portion. The forward boundary 24 of the unreinforced portion lies preferably some three-quarters of an inch rearward of the front vertical face 26 of the pad so that this boundary is situated near where the heel end of a woman's shoe having no heel attached (indicated by dot-and-dash lines in Figs. 3 and 4) engages the diaphragm and the unreinforced portion extends rearwardly to the vicinity of the ball line of the shoe.

By this means, when a full-length sole is being attached to a shoe, the comparatively flat portion of the forepart is pressed against the reinforced region of the diaphragm while the arched shank portion and the heel end portion are pressed against the unreinforced region. The forward narrower portion of the unreinforced region is of such width as to allow the heel end of the shoe to sink into it sufficiently (without causing the diaphragm to balloon) and to allow the sole to be pressed adequately against the shoe bottom while the wider rearward portion can distend sufficiently when pressure is applied to press against the upwardly and laterally curved portion of the shank of the shoe.

When a half sole is being attached to a shoe which already has a high heel attached to it, the toe end portion of the shoe is spaced farther forwardly on the pad

in such a position that a sufficient area of the unreinforced region will be able to extend upwardly when pressure is applied to the shoe and exert adequate pressure to force the heelward margin of the half-sole firmly against the sharply upward sloping portion of the shoe bottom which is immediately heelward of the ball line leading to the sharply curved shank portion. The reinforcement along the front of the diaphragm prevents ballooning forwardly and thus avoids pressure on the breast of the overhanging heel such as might tend to force it away from its seating on the shoe bottom.

With the arrangement above described, the diaphragm is sufficiently flexed in the unreinforced region to operate efficiently on the arched shank portion of the shoe bottom while ballooning or undesirable distention or fracture of the diaphragm is prevented by the nylon mesh reinforcement. Since this arrangement eliminates the use of the shaped rubber blocks above mentioned, heat will be conducted from the water in the pad to the shoe bottom as usual.

Having thus described my invention, what I claim as new and desire to secure by Letters Patent of the United States is:

1. A pad box diaphragm comprising two separate layers of nylon mesh embedded in rubber, each layer having an opening therein in the region which is to engage the shank portion of a shoe, the opening in one layer being larger than the opening in the other layer.

2. A pad box diaphragm according to claim 1 in which the margins of the layers of nylon about the openings are pinked.
